[57] CLAIM

The ornamental design for an athletic shoe sole, substantially as shown and described.

DESCRIPTION

FIG. 1 is a bottom plan view of an athletic shoe sole showing my new design;
FIG. 2 is an inner side elevational view thereof;
FIG. 3 is an outer side elevational view thereof;
FIG. 4 is a front elevational view thereof;
FIG. 5 is a rear elevational view thereof;
FIG. 6 is a bottom plan view of another embodiment of my new design of FIGS. 1-5;
FIG. 7 is an inner side elevational view thereof;
FIG. 8 is an outer side elevational view thereof;
FIG. 9 is a front elevational view thereof;
FIG. 10 is a rear elevational view thereof.
